COMBINED GRADING AND ROLLING MACHINES

Adryl Wade Gardner, Redlands, Calif.

Application June 25, 1953, Serial No. 363,985

13 Claims. (Cl. 37—146)

My invention relates to road building and maintaining machinery, and relates more particularly to road grading machines having rollers for simultaneously rolling the graded surface during each pass of the scraper.

It is an important object of my invention to provide a combination road grader and roller wherein a standard road grading machine may be fitted with rolling means to provide a single machine to perform on each pass first a grading function and then a rolling function immediately thereafter.

In the past, road graders have been provided with rolling equipment in the form of either a towed unit or in the form of a fixed rolling device attached to the grader chassis so that the roller may be lowered into engagement with the ground or may be elevated thereabove during periods of disuse. In the form of roller which is merely towed behind the road grader the roller has no function except that of compaction. That is to say, since the towed roller carries none of the weight of the grading machine there is no inter-relation between the weight of the machine which is supported by the roller and that which is supported by the grader drive wheels. In the form of rolling device which, according to the prior art, has been carried on the grader chassis, there is the inherent disadvantage that when the rolling mechanism is lowered into working contact with the ground the roller is held in a fixed relation with respect to the guide and traction wheels of the grader and thus the roller is not free to independently follow transverse and longitudinal variations in the grade surface.

Therefore, one very important object of the present invention is to provide in combination with a road grader a rolling device which compacts the grade material to a substantially uniform degree. To achieve this purpose, it is necessary that the rolling device not be rigidly mounted on the chassis of the grader. In cases in which the rolling device is rigidly attached to the grader chassis uniform compaction of the grade material is not achieved since the roller stresses the high spots of the material heavily but scarcely touches the lower spots. Moreover, when the rolling device is rigidly attached to the chassis, an elevation in the grade material which cannot be leveled by the compaction effort of the roller causes the roller to lift the grader chassis at the point of attachment, and such lifting causes the normal weight distribution on the wheels of the grader to be altered so that either steering of the grader is impaired or else the grader is hung up on the roller with its drive wheels suspended off the ground. This type of machine, therefore, is not satisfactory since it performs mainly to roll the grade material to a constant level rather than performing to roll the material to a uniform degree of compaction.

It is therefore a primary object of my invention to provide a combined grader and roller wherein not only are the rolls so mounted that they are free to follow both the transverse and longitudinal variations in the grade surface but so that the rolls and the drive wheels divide the weight of the machine according to a predetermined

ratio. In order to accomplish this purpose I have used a type of machine having a drive frame on each side of the machine, which frames are respectively pivotally mounted on the machine intermediate the ends of the frames. Drive is furnished through pivotal mounting points to shafts on the frames located forwardly of the pivot point, which shafts each carry a drive wheel. At the aft end of each frame is an extension frame which is rigidly secured thereto, each extension having a set of longitudinally aligned trunnions. Journaled in these trunnions are longitudinally disposed beams carrying stub axles transversely disposed therethrough, and a plurality of roller wheels are carried by these stub axles. By this means it will be seen that the weight of the machine, as applied to the point at which the said frames are attached to the sides of the machine, will be distributed to both the forward drive wheels and to the following roller wheels, and it will furthermore be seen that the individual frames on each side of the machine are free to oscillate about said transverse pivot points whereby the respective roller wheels and drive wheels will at all times bear their respective share of the weight of the machine. The oscillating of the frames about the said pivot points, therefore, permits both the drive wheels and the roller wheels to follow the longitudinal contours of the grade material, and the rocking of the stub axle beams about said longitudinally disposed trunnions will permit the roller wheels to follow any transverse variations in the contour of the grade material.

An additional important object of my invention is to provide means whereby the proportion of the weight respectively carried by the drive wheels and the roller wheels may be altered by the operator of the machine from his control station. So long as the operator does not choose to control the distribution of the weight between the respective drive wheels and roller wheels on each side of the machine, the proportion of the weight of the machine which is carried by said drive wheels and by said roller wheels will be predetermined by the length of the respective moment arms from the point of pivotal mounting of the frames to the drive wheels and to the roller wheels. However, when it becomes desirable to shift the weight distribution (for instance, for the purpose of throwing greater weight on the drive wheels so as to provide additional traction between the drive wheels and the grade surface) the weight distribution may be altered by means of a hydraulic cylinder and piston assembly whereby the angular position of the frames with respect to the chassis of the machine may be predetermined. In order to control this weight distribution I have provided a hydraulic piston and cylinder connected between the chassis of the machine and the respective frames on each side of the machine, said piston and cylinder assembly being pressurized by a source of hydraulic pressure to forcibly alter the angular position of each frame with respect to the chassis of the machine so as to alter the weight distribution on the respective drive wheels and roller wheels about the pivotal mounting of each frame on the chassis of the machine. By this means the weight carried by the traction wheels of the machine can be increased above the weight which these wheels would normally carry when said cylinders are not pressurized so as to provide additional traction between said wheels and the ground to keep the machine moving along the surface and to avoid slippage of the traction wheels.

Further objects of my invention include the provision of a strong and simple roller structure which will not only allow the scraping portion of the machine to operate with its full efficiency but which will at the same time contact the surface of the grade material after the latter has been scraped and roll the material to a uniform de-

gree of compaction, as distinguished from compaction to a level surface.

Further objects and advantages of my invention will become apparent during the more detailed description of my invention.

I will now describe with particularity the embodiment of my invention shown in the accompanying drawings wherein:

Figure 1 is a side elevation of the grader-roller combination.

Fig. 2 is a plan view thereof.

Fig. 3 is an enlarged side view of the rolling means and the traction wheels showing the same supported on a pivotally mounted framework which is a part of the standard road grader illustrated.

Fig. 4 is a view similar to Fig. 3 but showing the rolling mechanism and traction wheels riding different longitudinal elevations of the grade surface.

Fig. 5 is a rear view of the grader-roller shown in Figs. 1 and 2, in which the rolling means is shown following the surface of a non-level grade.

Fig. 6 is a view similar to Fig. 5 but showing the rolling means riding on a level surface.

Fig. 7 is a schematic diagram of the hydraulic circuit, showing the elements and arrangement thereof selectively distributing the weight of the aft end of the machine between the rollers and the traction wheels.

Fig. 8 is a sectional view showing one of the control valves of Fig. 7 in closed position.

Fig. 9 is a sectional view showing another of the control valves of Fig. 7 in open position.

Fig. 10 is a perspective view of one of the roller wheel axles showing the supporting beam and trunnion for providing transverse freedom of motion.

Referring to the drawings, the grader-roller includes most of the elements of a standard road grader, consisting principally of a main chassis which may be of any suitable construction and is designated 1 in its entirety. The machine further includes a conventional grader blade 2, a standard A-frame and circle assembly 3, and a standard blade lifting mechanism 4 by means of which the position of the grading blade 2 is controlled. A conventional instrument and control pedestal 5 supports a steering wheel 6 which controls steerable front wheels 7 on which the front end of chassis 1 rests. An operator's seat 8 is located on chassis 1 adjacent control pedestal 5.

Further elements of the standard form of road grader include an engine and engine housing 10, and a pair of tandem drive frames 20. Tandem drive frames 20 are a part of the standard form of road grader shown and are provided with traction wheel drive shafts 21 journaled in carriers 22 and 23. Figures 1, 2, 3 and 4 show forward traction wheels 24 mounted on those traction wheel drive shafts 21 which are carried by drive shaft carriers 22. In a standard road grader additional traction wheels, identical to traction wheels 24, would normally be mounted on and driven by the aft drive shafts 21, journaled in the aft drive shaft carriers 23. These additional traction wheels are not shown in the drawings since they are not employed according to this invention.

In the standard form of road grader shown in the drawings, the chassis 1 is supported at the rear on journals 25 on which each tandem drive frame 20 is pivotally mounted. Concentric with and journaled in journals 25 are the transmission drive shafts 26 which are connected through chain drives 26a to transmit power from the engine and main transmission to the drive shafts 21.

The description of the machine so far has included only the essential elements of a standard road grader with the rear traction wheels of the tandem drive removed.

The rolling means, according to my invention, comprises a rolling apparatus attached to the rearwardly ex-

tending portions of the tandem drive housings 20. The embodiment of the rolling means shown in the drawings includes two separate roller extension frames 27 rigidly attached to tandem drive frames 20. The extension frames 27 are each fitted with a pair of aligned trunnion bearings 27a in which are journaled trunnion beams 28, a perspective view of which is shown in Fig. 10. Aligned trunnion pins 29 are journaled in trunnion bearings 27a to permit free oscillation of trunnion beams 28. Projecting laterally from the trunnion beams 28 are roller wheel axles 30 on which are journaled a plurality of roller wheels 31. Oscillation of the trunnion beams 28 transversely of the grader-roller permits the roller wheels 31 to follow the ground contours as illustrated in Figs. 5 and 6.

Fixed to and extending downwardly from the outer side of each extension frame 27 is a member 32 which is provided with a vertical slot 33 which guides the extremity 30a of the roller wheel axle 30 when the trunnion beam 28 oscillates in trunnion bearings 27a, this structure permitting roller wheels 31 to follow transverse variations in the ground contour but limiting the angle through which the trunnion beams 28 may pivot.

It is to be understood that the roller wheels 31 carried by the roller extension frames 27 support the rearwardly extending portions of tandem drive frames 20 and replace the traction wheels which would be mounted on aft shafts 21 (journaled in drive shaft carriers 23) on the standard grader. In this manner tandem drive frames 20 are supported at both ends, at the forward ends by traction wheels 24 and at the aft ends by roller wheels 31.

As hereinbefore described it will be readily understood that the roller wheels 31 may follow both the longitudinal and the transverse variations in the grade surface.

An important provision of my invention is a hydraulic apparatus for controlling the pivotal position of the tandem drive frames 20 about supporting journals 25. This feature is in addition to the structure as hereinbefore described, and comprises a fluid pressure system including a pair of hydraulic cylinders 34 pivotally mounted as at 40 at their upper ends to brackets 39 on the chassis 1. The cylinders 34 are equipped with reciprocable pistons 35, having piston rods 36 pivotally connected at 37 to brackets 38 fixed to tandem drive frames 20, Figs. 3 and 4. Further elements of the hydraulic circuit as shown in Figs. 7, 8 and 9 include a sump 41 for oil or other similar liquid, the liquid flowing by suction through a pipe 50 to a gear pump 42. 51 denotes the outlet pipe leading from said pump, said pipe communicating through a T 69 and a pipe 70 with a valve casing 43 and with a bypass casing 47. Valve casing 43 communicates with a T 54 through pipe 52 and then through a pipe 61 to another T 57, thence through pipes 44 into the upper ends of the cylinders 34.

The valve casing 43 also communicates with a pipe 55 to a T 55 and through a pipe 62 to another T 56, thence through pipes 46 to the lower ends of the cylinders 34. T's 54 and 55 also communicate respectively through pipes 59 and 58 respectively to a second valve casing 45, said valve 45 being connected through a pipe 60 to an elevated expansion tank 49, which is returned to the sump 41 through pipe 63, T 64 and pipe 65. Valve casing 43 is returned to the sump 41 through pipe 66, T 67, pipe 68, T 64 and pipe 65. T 69 communicates with T 67 through pipe 71, pressure relief bypass valve 47, and pipe 72.

With the parts of the hydraulic circuit arranged as described, the manner in which the hydraulic controls operate can be readily understood. With the hydraulic circuit filled with oil or other operating fluid, and with the valves set as shown in Fig. 7, operating fluid is supplied under pressure against the upper side of pistons 35 in cylinders 34, causing pistons 35 and rods 36 to travel downwardly. Fluid thus displaced from the lower ends

of cylinders 34 by pistons 35 is discharged through pipes 46, 62, 53, valve 43, pipes 66, 68 and 65 to sump 41. When valve 43 is rotated by control lever 43a 90° counter-clockwise from the position shown in Fig. 7, fluid under pressure is supplied against the lower sides of pistons 35 in cylinders 34, causing pistons 35 and rods 36 to travel upwardly. Fluid thus displaced from the upper ends of cylinders 34 by pistons 35 is discharged through pipes 44, 61, 52, valve 43, pipes 66, 68 and 65 to sump 41. When valve 43 is rotated to closed position as shown in Fig. 8, pistons 35 and rods 36 are held against movement in either direction. Under such a condition, fluid delivered under pressure from the pump flows through pipes 51 and 71 through pressure relief by-pass valve 47 and is returned through lines 72, 68 and 65 to sump 41. It can thus be seen that pistons 35 and rods 36 can be forced to move in either direction and can also be held against movement, by selectively setting valve 43. Also it will be seen that forced movement of pistons 35 and rods 36 causes the tandem drive frames 20, at the respective opposite ends of which are mounted roller wheels 31 and traction wheels 24, to pivot around journals 25 to the position desired. In this manner, normal distribution of the weight between traction wheels 24 and roller wheels 31 can be altered and the ground pressure can be increased above the normal pressure on the traction wheels to provide additional traction when required. Such a requirement may be occasionally encountered in materials not providing good traction characteristics or when additional blade 2 cutting thrust is required. It is to be understood that in normal operation of the grader-roller, tandem drive frames 20 are permitted to pivot freely around journals 25 so that the load distribution between traction wheels 24 and roller wheels 31 is a natural function of the cantilever action of the tandem drive frames 20, and remains a constant.

Provision for the free pivoting of tandem drive frames 20 around journals 25 is provided in the hydraulic circuit by valve 45. With valve 43 in closed position as shown in Fig. 8, and with valve 45 in closed position as shown in Fig. 7, pistons 35 and piston rods 36 are held against movement in either direction, as hereinbefore described, and the tandem drive frames 20 are thus held against rotation about journals 25. However, when free rotation or pivoting of tandem drive frames 20 around journals 25 is desired, for normal operation of the grader-roller, valve 45 is rotated by control lever 45a to open position as shown in Fig. 9. With valve 45 in open position, pistons 35 and piston rods 36 are free to float in either direction in cylinders 34 so that the tandem drive frames 20 are then free to pivot around journals 25. When pivoting of the tandem drive frames 20 is in a direction causing downward travel of pistons 35, hydraulic fluid displaced from the lower ends of cylinders 34 flows through pipes 46, T 56, pipe 62, T 55, valve 45, pipe 59, T 54, pipe 61, T 57 and pipes 44 to the upper ends of cylinders 34. Since downward travel of pistons 35 and rods 36 does not displace a volume of hydraulic fluid as great as the volume of cylinders 34 above pistons 35, additional hydraulic fluid is drawn by suction from the overflow tank 49 through pipe 60, valve 45, pipe 59, T 54, pipe 61, T 57 and pipes 44. When pivoting of the tandem drive frames 20 around journals 25 is in a direction causing upward travel of pistons 35, more hydraulic fluid is displaced than the increased volume of the portions of the cylinders below the pistons 35 can accommodate. Consequently, the excess hydraulic fluid flows through the same circuit afore described, in reverse direction, to overflow tank 49. In this manner, pistons 35 and rods 36 are free to travel in either direction in cylinders 34 and the tandem drive frames 20 are thus free to pivot in either direction around journals 25, thereby permitting the roller wheels 31 and traction wheels 24 to follow the ground contours without disturbing the normal weight carried by either.

Other apparatus for controlling forced position of the tandem drive frames 20 around journals 25, and thus applying more than the normal loads on the traction wheels 24, may be employed. The hydraulic means herein described is shown as only one means for providing the desired control action.

I do not limit my invention to the exact form shown in the drawings, for obviously changes may be made within the scope of the claims.

10 I claim:

1. A combined road material scraper and roller comprising a chassis; ground engaging steerable wheels at one end of said chassis; two independent frames, each pivotally connected intermediate its longitudinal ends 15 on the other end of said chassis on opposite sides thereof, the respective pivots lying along a transverse axis; a ground engaging drive wheel carried by each frame at one end thereof; a motor connected to drive said drive wheels; transverse axle means carried by each 20 frame at the end thereof opposite the drive wheel, said axle means occupying a common transverse vertical plane and extending toward each other substantially to the transverse center of the chassis; a plurality of ground engaging rollers freely journaled on each axle means, the 25 weight of the machine as applied to said frames at said transverse axis normally being distributed between said rollers and said drive wheels; road material scraper means carried on said chassis between said frame means and said steerable wheels; and power actuated means connected between each frame and said chassis for applying a tilting pressure to said frames about said transverse axis to alter the normal weight distribution between said rollers and said drive wheels.

2. In a device as set forth in claim 1, the roller carrying end of each frame having opposed longitudinally aligned trunnion bearings, a beam journaled in said bearings, said axle means comprising an axle fixed through the center of each beam, said rollers being symmetrically journaled on each axle with respect to said trunnion bearings; and means to limit the angle through which said axle may tilt from horizontal.

3. In a device as set forth in claim 1, said power actuated means comprising a piston and cylinder connected between one end of each frame and said chassis; a source 45 of fluid pressure; valve means to selectively apply fluid pressure to either end of said cylinders to cause the pistons to be moved therein; and valve means to connect together the respective ends of said cylinders to permit free motion of the pistons therein, the pistons being 50 locked in the cylinders when both valves are closed.

4. A combined road material scraper and roller comprising a chassis; ground engaging steerable wheels at one end of said chassis; frame means pivotally connected intermediate its longitudinal ends to the other end of said 55 chassis along a transverse axis; transversely spaced ground engaging drive wheels carried by said frame means at one end thereof; a motor connected to drive said drive wheels; a plurality of ground engaging rollers freely journaled on said frame means at the end thereof opposite 60 said drive wheels, the weight of the machine as applied to said frame means at said transverse axis normally being distributed between said rollers and said drive wheels; road material scraper means carried on said chassis between said frame means and said steerable wheels, the 65 roller carrying end of the frame means having pairs of opposed longitudinally aligned trunnion bearings; and a beam journaled in each pair of bearings, said beams each having fixed through its center a transversely disposed axle, said rollers being symmetrically journaled on 70 said axles with respect to the associated beam.

5. In a device as set forth in claim 4, power actuated means connected between said frame means and said chassis comprising a piston and cylinder connected between one end of said frame means and said chassis; a 75 source of fluid pressure; valve means to selectively apply

fluid pressure to either end of said cylinder to cause the piston to be moved therein; and valve means to connect together the respective ends of said cylinder to permit free motion of the piston therein.

6. A combined road material scraper and roller comprising a chassis; ground engaging steerable wheels at one end of said chassis; two independent frames, each pivotally connected intermediate its longitudinal ends to the other end of said chassis on opposite sides thereof, the respective pivots lying along a transverse axis; a ground-engaging drive wheel carried by each frame at one end thereof; a motor connected to drive said drive wheels; a plurality of ground engaging rollers freely journaled on each frame at the end thereof opposite the drive wheel, the weight of the machine as applied to said frames at said transverse axis normally being distributed between said rollers and said drive wheels; road material scraper means carried on said chassis between said frames and said steerable wheels, the roller carrying end of each frame having opposed longitudinally aligned trunnion bearings; and a beam journaled in said bearings, said beam having fixed through its center a transversely disposed axle, said rollers being symmetrically journaled on said axis with respect to said trunnion bearings.

7. In a device as set forth in claim 6, means on each frame engaging each axle to limit the angle through which said axle may tilt from horizontal.

8. In combination with a scraper-type road material grading machine having a chassis carrying a scraper and having steerable wheels at one end, and having at the other end two longitudinally disposed frames, one on each side of the chassis and each frame being independently pivotally mounted to the chassis along a transverse axis intermediate its longitudinal ends and each frame carrying a motor-driven drive wheel at one end; roller supporting means fixed to each frame at the end opposite the drive wheel and including axle means occupying a common transverse vertical plane and said axle means extending toward each other substantially to the transverse center of the chassis; rollers freely journaled on said axle means, the combined width of the respective rollers contacting the road material across at least the full width of the machine; and power actuated means respectively connected between each frame and said chassis whereby the frames may be tilted to alter the normal distribution of the proportion of the weight of the machine carried by said drive wheels and by said rollers.

9. In a device as set forth in claim 8, the roller carrying end of each frame having opposed longitudinally aligned trunnion bearings, a beam journaled in said bearings, said axle means comprising an axle fixed through

the center of each beam, said rollers being symmetrically journaled on each axle with respect to said trunnion bearings, and means to limit the angle through which said axle may tilt from horizontal.

10. In a device as set forth in claims 8, said power actuated means comprising a piston and cylinder connected between one end of each frame and said chassis; a source of fluid pressure; valve means to selectively apply fluid pressure to either end of said cylinders to cause the pistons to be moved therein; and valve means to connect together the respective ends of said cylinders to permit free motion of the pistons therein, the pistons being locked in the cylinders when both valves are closed.

11. In combination with a road material grading machine having a chassis and having steerable wheels at one end, and having at the other end two longitudinally disposed frames on opposite sides of the chassis, each frame being independent and pivotally mounted to the chassis along a transverse axis intermediate its longitudinal ends and each frame carrying a motor-driven drive wheel at one end; two independent roller supporting means each fixed to a frame at the end opposite the drive wheel and each including axle means occupying a common transverse vertical plane; and rollers freely journaled on said axle means.

12. In a device as set forth in claim 11, power actuated means respectively connected between each frame and said chassis whereby the frames may be tilted to alter the normal distribution of the proportion of the weight of the machine carried by said drive wheels and by said rollers.

13. In a device as set forth in claim 11, the roller carrying end of each frame having opposed longitudinally aligned trunnion bearings, a beam journaled in said bearings, said axle means comprising an axle fixed through the center of each beam, said rollers being symmetrically journaled on each axle with respect to said trunnion bearings; and means to limit the angle through which said axle may tilt from horizontal.
